US00D795350S

(12) **United States Design Patent** (10) **Patent No.:** **US D795,350 S**
(45) **Date of Patent:** ** *Aug. 22, 2017

(54) **CONTROLLER**

(71) Applicant: **Microsoft Corporation**, Redmond, WA (US)

(72) Inventors: **Monique Chatterjee**, Seattle, WA (US); **Richard T. Hanks**, Seattle, WA (US); **Matthew Harvey**, Seattle, WA (US); **Austin Porter**, Seattle, WA (US); **William Bennett Mabry**, Seattle, WA (US)

(73) Assignee: **Microsoft Corporation**, Redmond, WA (US)

(*) Notice: This patent is subject to a terminal disclaimer.

(**) Term: **15 Years**

(21) Appl. No.: **29/567,504**

(22) Filed: **Jun. 9, 2016**

(51) LOC (10) Cl. **21-01**

(52) U.S. Cl.

USPC **D21/333**

(58) **Field of Classification Search**

(57)

CLAIM

The ornamental design for a controller, as shown and described.

DESCRIPTION

FIG. 1 is a perspective front view of a controller showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the remainder of the controller in FIGS. 1–7 is for environmental purposes only and forms no part of the claimed design.

1 Claim, 7 Drawing Sheets
